UNITED STATES PATENT OFFICE.

THEODORE F. DE WITT, OF OVID, MICHIGAN.

FENCE.

SPECIFICATION forming part of Letters Patent No. 692,991, dated February 11, 1902.

Application filed April 30, 1900. Renewed June 3, 1901. Serial No. 62,935. (No model.)

To all whom it may concern:

Be it known that I, THEODORE F. DE WITT, a citizen of the United States, residing at Ovid, in the county of Clinton, State of Michigan, have invented certain new and useful Improvements in Fences; and I do declare the following to be a full, clear, and exact description of the invention, such as will enable others skilled in the art to which it appertains to make and use the same, reference being had to the accompanying drawings, and to the figures of reference marked thereon, which form a part of this specification.

This invention relates to fences; and it consists in the construction and arrangement of parts hereinafter fully set forth, and pointed out particularly in the claims.

The object of the invention is to produce a fence that will be light, strong, durable, and inexpensive and in which the arrangement is such as to enable the fence to be supported without the use of posts and permit the moving of said fence from place to place.

The above object is attained by the construction illustrated in the accompanying drawings, in which—

Figure 1 is a perspective view showing two panels of a fence made in accordance with my invention. Fig. 2 is an enlarged elevation 30 of the meeting ends of the two panels of fence, showing the manner of joining said panels. Fig. 3 is a transverse section through the fence as on line 3 3 of Fig. 2. Fig. 4 is a horizontal section as on line 4 4 of Fig. 1.

Referring to the characters of reference, 1 designates a central longitudinal rail of a length sufficient to form one panel of the fence, said rail being squared at the ends and secured to the vertical end posts 2 by spikes, 40 as shown by dotted lines 3 in Fig. 4, or by any other suitable means. Secured to the opposite face of the longitudinal rail 1 at proper intervals are the slats 4, whose ends curve together and are secured by longitudinal strands of wire 5, which embrace said slats and are twisted together therebetween, so as to firmly hold said slats and establish supporting-strands therefor extending between the end posts 2 of the panels of the fence. 45 There may be as many as desired of the twisted strands 5, which are equally divided

on opposite sides of the central rail, so as to equalize the strain upon the opposite end of the post 2 and firmly bind all parts together.

The fence-panel, comprising the end posts 2, 55 connected by the longitudinal rail 1 and having mounted thereon the slats intermediate said posts secured by the twisted or interwoven strands of wire, may be readily connected by joining the end posts of the adjacent panels in the manner shown, which consists in forming of wire of suitable size a yoke 6, adapted to embrace said posts, as clearly shown in Fig. 4, and which is secured thereto by means of confining-staples 7, driven 65 into said posts astride of said yoke. To prevent accidental withdrawal of the yokes, their end portions are bent, as shown at 8, whereby they are securely retained in place. When it is desired to remove the fence, the yokes 6 70 may be withdrawn for the purpose of detaching the panels of the fence by straightening out the bent end portions 8, as will be readily understood.

This improved fence is designed to be 75 supported without the use of posts and is anchored at the junction of the panels by means of the triangular brace or truss 9, which is preferably formed of wire and is secured to the middle of the yoke 6, from which it extends downwardly on each side to suitable anchoring-blocks 10, thence horizontally to the bottom of the fence, and is attached to the lower yoke 6 thereof, forming a triangular brace, which prevents the tipping of the fence 80 and holds the bottom thereof from swaying, forming a structure which may be readily moved to change the line of the fence and which when set up is strong, durable, and comparatively inexpensive. 85

Having thus fully set forth my invention, what I claim as new, and desire to secure by Letters Patent, is—

1. In a fence, the combination of the longitudinal rail, the posts attached to the opposite ends thereof, the fence-slats mounted opposite each other upon said rail and between said posts and the longitudinal wire strands extending between said posts and embracing the ends of said slats. 95

2. In a fence, the combination of a plurality of panels each comprising a longitu-

dinal rail having posts secured to the opposite ends thereof, opposed slats mounted upon said rail intermediate the posts, strands of twisted wire extending between said posts and embracing the ends of said slats, and means for detachably uniting the meeting posts of said panels.

In testimony whereof I sign this specification in the presence of two witnesses.

THEODORE F. DE WITT.
